(57) **CLAIM**

The ornamental design for a hinged wall profile door, as shown and described.

DESCRIPTION

FIG. 1 is a front perspective view of the hinged wall profile door showing our new design;

FIG. 2 is a front elevation view of the hinged wall profile door of FIG. 1;

FIG. 3 is a rear elevation view of the hinged wall profile door of FIG. 1;

FIG. 4 is a left side elevation view of the hinged wall profile door of FIG. 1;

FIG. 5 is a right side elevation view of the hinged wall profile door of FIG. 1;

FIG. 6 is a top plan view of the hinged wall profile door of FIG. 1; and,

FIG. 7 is a bottom plan view of the hinged wall profile door of FIG. 1.

The dashed broken lines in FIG. 3 define the bounds of the claimed design and form no part thereof.
